COOLING JACKET AND CYLINDER
CONSTRUCTIONThomas L. Sherman, Springfield, Ohio, assignor
to The Steel Products Engineering Co., Spring-
field, Ohio, a corporation of Ohio

Application March 22, 1946, Serial No. 656,293

8 Claims. (Cl. 123—173)

1

This invention relates to crankless mechanisms, and more particularly to a cooling system for an internal combustion engine of the crankless type wherein the reciprocating movement of the pistons is translated into rotary movement of a shaft through a slant or swash plate mounted for rotation with said shaft.

One of the principal objects of the invention is to provide a simple and efficient cooling system for internal combustion engines of the above type and having particular application to such engines wherein each cylinder has a pair of opposed pistons mounted therein for reciprocation in opposite directions.

Another object is to provide a cooling system for such engines which is capable of supplying separate parallel flows of coolant to each cylinder to maintain a substantially uniform temperature in all the cylinders.

It is also an object of the invention to provide a cooling system for such engines which includes passages for directing a full and adequate flow of coolant into contact with the walls of the exhaust ducts to increase the cooling effect for these walls.

A further object is to provide a cooling system for such engines which includes passages for dividing the coolant substantially equally among all the cylinders to equalize their temperatures.

Other objects and advantages will be apparent from the following description, the accompanying drawings and the appended claims.

In the drawings, in which like reference characters designate like parts throughout—

Fig. 1 is a view partly in side elevation and partly in vertical section illustrating a crankless engine provided with a cooling system constructed in accordance with the invention;

Fig. 2 is a composite view in vertical section of the engine shown in Fig. 1, the left half of the section being taken on the line 2a—2a in Fig. 1 and the right half being taken on the line 2b—2b in Fig. 1;

Fig. 3 is a section similar to Fig. 2, the left half being taken on the line 3a—3a in Fig. 1 and the right half being taken on the line 3b—3b in Fig. 1;

Fig. 4 is a half section taken on the line 4—4 in Fig. 1;

Fig. 5 is a half view looking in the direction indicated by the line 5—5 in Fig. 1 and showing the outer end of the engine;

Fig. 6 is a partial view in side elevation illustrating an engine and cooling system of the type shown in Figs. 1—5 as applied to an airplane;

2

Fig. 7 is a view looking generally in the direction indicated by the line 7—7 in Fig. 6 and showing the outer end of the construction of Fig. 6, with parts broken away to show more clearly the structural details; and

Fig. 8 is a fragmentary sectional view illustrating a modification of a structural detail of the engine shown in Fig. 1.

Referring to the drawings which disclose a preferred embodiment of the invention, the engine is of the opposed piston, crankless type such as that shown, for example, in Patent No. 2,250,608, issued July 29, 1941, to the present inventor and assigned to the same assignee as this invention. It includes five cylinders indicated generally by the reference character 10 arranged circumferentially around and equidistant from a slant shaft 11 parallel thereto. Each of the cylinders is adapted to receive a pair of opposed pistons 12 and 13 adapted for reciprocation in opposite directions and connected through suitable bridge means 14 to slants or swash plates 15 positioned at each end of the engine within housings 16 and 17 and suitably secured to slant shaft 11, these parts being shown diagrammatically in Fig. 1 and a similar arrangement of pistons and slants and means for connecting slant shaft 11 to main driven shaft 18 being shown in the above mentioned patent. A blower 20 or other auxiliary unit at the opposite end of the engine from main shaft 18 may be similarly placed in driven connection with slant shaft 11. Each of cylinders 10 includes an intake duct 21 through which air or mixture is taken in through a series of ports 22, a combustion chamber 23 disposed approximately centrally of the cylinder, and a ring of exhaust ports 24 leading to outlet duct 25.

Element 30 represents a pump for the cooling system provided with an intake 31 which may be connected to a radiator for the circulating cooling fluid. A pipe 32 conveys the coolant from the pump 30 to an annular chamber 35, which is disposed axially between the intake ducts 21 and the combustion chambers 23 of the cylinders, and the radially inner wall 34 of which surrounds slant shaft 11. This chamber 35 serves as a general supply chamber for the coolant for the various cylinders and its shape in cross section is clearly shown in the left half of Fig. 2. The annular portion 36 adjacent the central plane of the engine is provided with circumferentially spaced circular apertures for each of the five cylinders 10, and the diameter of these apertures 55 is sufficiently larger than the outer diameter of

each cylinder so that when the cylinder is mounted in place, there remains an annular passage 37 surrounding the cylinder which serves to convey coolant towards the combustion chamber and exhaust ports of the cylinder. The outer wall of each of these passages 37 is provided by a generally cylindrical portion 38 which extends inwardly from the outer casing 39 for the central part of the engine and may be formed integrally therewith as shown at the right in Fig. 2.

In engines of the type shown in Fig. 1, the portions of the cylinder exposed to the greatest amount of heat are the combustion chamber 23 and the exhaust duct 25 and its passages and chambers through which the hot gases escape from the cylinder. The invention accordingly makes special provision for effective cooling of these portions of the cylinder walls. Each of cylinders 10 is provided with an outwardly extending central flange of band overlying the combustion chamber 23 and serving also to locate the cylinder in properly spaced relation with the circular walls 38. The outer surface of this band is milled to provide a plurality of grooves 40, which extend in the general direction of the length of the cylinder completely across the locating band. Grooves 40 alternate with rib-like portions 41 which remain from the flange and engage in locating contact with the inner surface of walls 38, this construction being most clearly shown in Fig. 2. Grooves 40 provide communication for coolant from annular passage 37 to a corresponding annular passage 42 which lies axially between the combustion chamber and the exhaust duct of the cylinder. Since the presence of rib portions 41 restricts the total cross sectional area of grooves 40 with respect to their adjacent annular passages 37 and 42, this results in substantially increasing the velocity of the coolant in passing through grooves 40, and since during this state of increased velocity the coolant is in direct contact with the outer surface of the cylinder wall overlying the combustion chamber, this provides for increased cooling effect and rapid transfer of heat from the combustion chamber to prevent overheating.

The annular passage 42 is terminated at its axially outer end by a peripheral flange or band 45 on the cylinder in which the exhaust ports 24 are formed, these ports being cut through the cylinder wall substantially at the mid-portion of this band 45. The exhaust gases pass through these ports into the exhaust chamber and outlet duct 25, which is partly annular in cross-section as shown in the right half of Fig. 3, and thence to the atmosphere. These ports 24 are arranged in spaced relation around the cylinder, and the remaining portions of flange 45 and the cylinder wall between the slots form a plurality of bar members 46 which extend across the exhaust chamber as shown in Fig. 1 and at the right in Fig. 3. The exhaust gases which pass through ports 24 are very hot, and in the course of operation of the engine these bar portions will tend to absorb a substantial amount of this heat. It is accordingly desirable to provide for cooling these bars and also, for the same reason as in the case of the combustion chamber, to provide for increasing the velocity of the coolant in contact with the bars. To accomplish this result, bars 46 and the flange portions at each end thereof are drilled at 47 to provide a series of restricted channels which serve to conduct coolant at increased velocity from annular passage 42 across

the exhaust chamber to an outer chamber 50 shown more clearly in Fig. 4.

In order next to provide for cooling the remainder of the exhaust chamber, the direction of the coolant is reversed from chamber 50, and it is conducted back through an annular passage 51 which is formed between the inner walls 52 of exhaust chambers 25 and cylindrical member 53 which surrounds slant shaft 11 and corresponds to member 34 at the opposite end of the engine. This chamber 51 is generally star-shaped in cross section, as shown in Fig. 3, and connects at its inner end with an annular chamber 54 generally similar in outline to the supply chamber 35 and positioned axially between the exhaust ducts 25 and combustion chambers 23 of the cylinders, as shown in Fig. 1. Chamber 54 in turn connects with a plurality of generally sector-shaped passages 55, there being one of these passages 55 positioned between each pair of cylinders 10 and formed by the outer casing 56 of this portion of the engine and the side walls 57 of exhaust chambers 25, which connect at 58 with the inner walls 52 of the exhaust chambers, and the extended portions 59 of these side walls 57. Each of these passages 55 is provided at its axially outer end with a discharge port 60 for coolant, and these ports may be connected with a suitable radiator for a circulating system, as is shown in Figs. 6 and 7, each of these ports being shown as provided with a fitting 61 for use in making such a connection. In order also to permit controlled leakage and the escape of trapped air and the like, a small opening may be provided as indicated at 65 at the top of annular chamber 50.

With the above construction the coolant initially transmitted to supply chamber 35 by way of pump 30 and pipe 32 is divided substantially equally among the five cylinders and forced through the annular passages 37 surrounding each cylinder. The grooves 40 in flange 41 which overlie the combustion chamber of each cylinder provide for restricting the passage of the coolant and thus increase its velocity, which is a desirable result in view of the substantial volume of heat evolved in this portion of the cylinder as a result of combustion in operation. The drilled holes 47 in bars 46 similarly restrict the passage of coolant from annular passage 40 to annular chamber 50, which is desirable for the same reason as in the case of the combustion chamber since the exhaust fumes which carry substantial heat pass out through the ports 24 adjacent bars 46, and the increased velocity of coolant through these bars aids in carrying off the heat absorbed by the bars from the exhaust fumes. Also, since this construction provides for resistance to the flow of coolant adjacent the combustion chambers and exhaust chambers which are large in effect in comparison with the remainder of the system, this results in effectively directing parallel flows of coolant around each cylinder which will be substantially equal in amount. The double reversal of the direction of passage of the coolant after it reaches chamber 50 also aids in effective cooling of the exhaust passages, since during its course from annular chamber 50 to discharge ports 60 the coolant flows over substantially the entire outer surface of the wall members surrounding exhaust chambers 25. This provides for thorough and efficient cooling of the exhaust chambers and exhaust ducts, which are in normal operation at portions of the engine subjected to the maximum intensity of heat.

Figs. 6 and 7 illustrate the application of the

cooling system shown in Figs. 1-5 to an airplane engine. In Figs. 6 and 7 the fittings 61 at the discharge ports are shown as each provided with a pipe 70 communicating with a manifold 71 which is generally annular and connects at 72 with the header 73 of a radiator 74. This radiator is shown as also of annular shape and surrounds the front slant housing 75 through which the driven shaft 76 extends for connecting with a propeller. Radiator 74 is provided with a suitable filler cap 77 and a pipe 78 adapted to return the coolant to a pump such as pump 30 in Fig. 1 to complete the circulating cooling system. A small pipe 79 connecting the top of the engine with header 73 provides for controlled leakage and the escape of trapped air and the like and may connect with the opening 65 shown in Fig. 1. Element 80 shown in dotted lines in Fig. 6, represents an exhaust manifold connecting the exhaust ports 81 corresponding to chambers 25 of each cylinder. The dotted outline at 85 represents a streamlined cowling or like structure which may readily enclose the engine and cooling system for minimum resistance to air flow in flight.

If it appears in operation that adequate cooling of the exhaust chambers is obtained without passing all of the coolant through passage 51, means may be provided for permitting some of the coolant to bypass this passage and flow directly to chamber 54 and passage 55. Such a bypass structure is shown in Fig. 8, wherein the chamber 50' which corresponds to chamber 50 connects with chamber 54' not only through passage 51' but also through passage 55', the extended wall portion corresponding to portion 59 in Figs. 1 and 4 being eliminated. Elements 52', 57' and 58' in Fig. 8 correspond to elements 52, 57 and 58, respectively, in Fig. 1. A tube 90 has one end mounted in discharge port 60', and its other end 91 extends through passage 55' into chamber 54' and is bent inwardly towards the central axis of the engine. With this construction, the coolant is divided after leaving chamber 50' with part traveling through passage 51' to chamber 54' as in Fig. 1, and the remainder traveling through passage 55' in the opposite direction from its direction through the corresponding passage 55 in Fig. 1 in order to reach inner end 91 of tube 90 to the discharge part. This will still, however, as in Fig. 1, provide for directing coolant into contact with all the outer surfaces of the wall members forming the exhaust chambers, the difference being that whereas in Fig. 1 all the coolant passes through all the passages surrounding the exhaust chambers, with the construction of Fig. 8, part of the coolant acts on some of these chamber walls and the remainder on the other chamber walls.

While the form of apparatus herein described constitutes a preferred embodiment of the invention, it is to be understood that the invention is not limited to this precise form of apparatus, and that changes may be made therein without departing from the scope of the invention which is defined in the appended claims.

What is claimed is:

1. In a crankless mechanism of the character described and including a plurality of cylinders circumferentially disposed in parallel relation about a central shaft, each cylinder having a substantially centrally located combustion chamber and an annular exhaust chamber positioned between said combustion chamber and one outer end thereof, and a pair of opposed pistons mounted in each cylinder for reciprocation in opposite

directions parallel to said shaft, a cooling system comprising, in combination, means providing an annular supply chamber for coolant surrounding said shaft and disposed axially at the opposite side of said combustion chambers of said cylinders from said exhaust chambers, means for supplying coolant to said annular chamber, means providing a second annular chamber coaxial with said annular supply chamber and positioned between said exhaust chambers and the adjacent outer ends of said cylinders, means providing passages for said coolant from said annular supply chamber to said outer annular chamber, said passage-providing means directing said coolant into contact with the walls of said cylinders, and means providing an outlet for said coolant from said outer annular chamber.

2. In a crankless mechanism of the character described and including a plurality of cylinders circumferentially disposed in parallel relation about a central shaft, each having a substantially centrally located combustion chamber and an annular exhaust chamber positioned between said combustion chamber and one outer end thereof, and a pair of opposed pistons mounted in each cylinder for reciprocation in opposite directions parallel to said shaft, a cooling system comprising, in combination, means providing an annular supply chamber for coolant surrounding said shaft and disposed axially at the opposite side of said combustion chambers of said cylinders from said exhaust chambers, means for supplying coolant to said annular chamber, means providing a second annular chamber coaxial with said annular supply chamber and positioned between said exhaust chambers and the adjacent outer ends of said cylinders, means providing passages for said coolant from said annular supply chamber to said outer annular chamber, said passage-providing means directing said coolant into contact with the walls of said cylinders, and means providing a third annular chamber axially intermediate said first named annular chambers, means providing a passage for said coolant from said outer annular chamber to said intermediate annular chamber and directing said coolant into contact with the outer walls of said exhaust chambers, and means providing an outlet for said coolant from said intermediate annular chamber.

3. In a crankless mechanism of the character described and including a plurality of cylinders circumferentially disposed in parallel relation about a central shaft, each having a substantially centrally located combustion chamber and an annular exhaust chamber positioned between said combustion chamber and one outer end thereof, and a pair of opposed pistons mounted in each cylinder for reciprocation in opposite directions parallel to said shaft, a cooling system comprising, in combination, means providing an annular supply chamber for coolant surrounding said shaft and disposed axially at the opposite side of said combustion chambers of said cylinders from said exhaust chambers, means for supplying coolant to said annular chamber, means providing a second annular chamber coaxial with said annular supply chamber and positioned between said exhaust chambers and the adjacent outer ends of said cylinders, means providing passages for said coolant from said annular supply chamber to said outer annular chamber, said passage-providing means directing said coolant into contact with the walls of said cylinders, means providing a third annular chamber coaxial with said outer annular chamber and positioned between said exhaust chambers and the adjacent outer ends of said cylinders, means providing passages for said coolant from said outer annular chamber to said third annular chamber and directing said coolant into contact with the outer walls of said exhaust chambers, and means providing an outlet for said coolant from said third annular chamber.

7
nular chamber axially intermediate said annular chambers and directing said coolant into contact with the outer walls of said exhaust chambers, and means providing a plurality of outlet passages for said coolant from said intermediate annular chamber and directing said coolant into contact with other portions of the outer walls of said exhaust chambers.

4. In a crankless mechanism of the character described and including a plurality of cylinders circumferentially disposed in parallel relation about a central shaft, each having a substantially centrally located combustion chamber and an annular exhaust chamber positioned between said combustion chamber and one outer end thereof, and a pair of opposed pistons mounted in each cylinder for reciprocation in opposite directions parallel to said shaft, a cooling system comprising, in combination, means providing an annular supply chamber for coolant surrounding said shaft and disposed axially at the opposite side of said combustion chambers of said cylinders from said exhaust chamber, means providing a second annular chamber coaxial with said annular supply chamber and positioned between said exhaust chambers and the adjacent outer ends of said cylinders, means providing an annular passage for coolant surrounding each of said cylinders and connecting with both said annular supply chamber and said outer annular chamber, a locating member positioned within each said annular passage substantially overlying the combustion chamber of the adjacent cylinder and having outer dimensions substantially equal to the inner dimensions of said passage, means providing a plurality of grooves across said locating member parallel to the axis of said cylinder, said grooves providing for restricted travel of said coolant through said annular passage and in contact with the outer wall of said combustion chamber, and means providing a plurality of outlet passages for said coolant from said outer annular chamber and directing said coolant into contact with the outer walls of said exhaust chambers.

5. In a crankless mechanism of the character described and including a plurality of cylinders circumferentially disposed in parallel relation about a central shaft and each having a substantially centrally located combustion chamber and an annular exhaust chamber positioned adjacent one outer end thereof, a cooling system comprising, in combination, means providing a supply chamber for coolant, means for supplying coolant to said supply chamber, means providing an annular chamber between said exhaust chamber and the adjacent outer ends of said cylinders, means providing an annular passage for coolant surrounding each of said cylinders and connecting with both said supply chamber and said outer annular chamber, a circumferential band on each of said cylinders axially overlying the exhaust chamber thereof, means providing a plurality of ports extending radially through each said band providing ducts for exhaust from said cylinder to said exhaust chamber, means providing a plurality of passages parallel to the axis of each cylinder extending through said band and through the material thereof between said ports, said passages extending from the adjacent annular passage to said outer annular chambers, and being of substantially less total cross sectional area than the corresponding area of said adjacent annular passage and providing for restricted passage of coolant therethrough

5
and for increasing the velocity of travel of said coolant, and means providing a plurality of outlet passages for said coolant from said outer annular chamber and directing said coolant into contact with the outer walls of said exhaust chambers.

6. In a crankless mechanism of the character described and including a plurality of cylinders circumferentially disposed in parallel relation about a central shaft and each having a substantially centrally located combustion chamber and an annular exhaust chamber positioned adjacent one outer end thereof, a cooling system comprising, in combination, means providing an annular supply chamber for coolant surrounding said shaft and disposed axially at the opposite side of said combustion chambers of said cylinders from said exhaust chambers, means for supplying coolant to said annular chamber, means providing a second annular chamber coaxial with said supply chamber and positioned between said exhaust chambers and the adjacent outer ends of said cylinders, means providing an annular passage for coolant surrounding each of said cylinders and connecting with both said supply chamber and said outer annular chamber, a locating member substantially overlying the combustion chamber of each cylinder and having outer dimensions substantially equal to the inner dimensions of said annular passages, means providing a plurality of grooves across said locating member parallel to the axis of said cylinder, said grooves providing for restricted travel of said coolant through said annular passage and in contact with the outer wall of said combustion chamber, means providing a third annular chamber axially intermediate said annular chambers and directing said coolant into contact with the outer walls of said exhaust chambers, and means providing a plurality of outlet passages for said coolant from said intermediate annular chamber and directing said coolant into contact with other portions of the outer walls of said exhaust chambers.

45
7. In a crankless mechanism of the character described and including a plurality of cylinders circumferentially disposed in parallel relation about a central shaft, each cylinder having a substantially centrally located combustion chamber and an annular exhaust chamber positioned between said combustion chamber and one outer end thereof, and a pair of opposed pistons mounted in each cylinder for reciprocation in opposite directions parallel to said shaft, a cooling system comprising, in combination, means providing an annular chamber for coolant surrounding said shaft and disposed axially at the opposite side of said combustion chambers of said cylinders from said exhaust chamber, means providing a second annular chamber coaxial with said first named annular chamber and positioned between said exhaust chambers and the adjacent outer ends of said cylinders, means for supplying coolant to one of said annular chambers, means providing connecting passages for said coolant between said annular chambers, said passage-providing means directing said coolant into contact with the walls of said cylinders, and means separate from said passage-providing means providing communication between said annular chambers for continuous circulation of said coolant through said chambers and said passages.

8. In a crankless mechanism of the character described and including a plurality of cylinders

circumferentially disposed in parallel relation about a central shaft, each cylinder having a substantially centrally located combustion chamber and an annular exhaust chamber positioned between said combustion chamber and one outer end thereof, and a pair of opposed pistons mounted in each cylinder for reciprocation in opposite directions parallel to said shaft, a cooling system comprising, in combination, means providing a first annular chamber for coolant surrounding said shaft and disposed axially at the opposite side of said combustion chambers of said cylinders from said exhaust chambers, means providing a second annular chamber coaxial with said first annular chamber and positioned between said exhaust chambers and the adjacent outer ends of said cylinders, means providing passages for coolant between said annular chambers, said passage-providing means directing coolant passing therethrough into contact with the walls of said cylinders, means providing a third annular chamber axially intermediate

said first and second annular chambers means providing a passage for coolant between said second and third annular chambers adapted to direct coolant passing therethrough into contact with the outer walls of said exhaust chambers, and means separate from said second annular chamber providing a passage for coolant between said first and third annular chambers for continuous circulation of coolant through said three annular chambers and said passages.
